US00D439152S

(12) **United States Design Patent** (10) Patent No.: **US D439,152 S**
Davis (45) Date of Patent: ** Mar. 20, 2001

(54) **COMPRESSED FABRIC ARTICLE PACKAGE HAVING A SIMULATED VAN SHAPE** 4,643,349 * 2/1987 Sheffer 229/116.4
4,646,959 * 3/1987 Sheffer 229/116.4

(76) Inventor: **Alan Davis**, 5830 Oberlin Dr., Suite 202, San Diego, CA (US) 92121

* cited by examiner

(**) Term: **14 Years**

Primary Examiner—Terry A. Wallace

(21) Appl. No.: **29/117,668**

(74) Attorney, Agent, or Firm—Brown Martin Haller & McClain, LLP

(22) Filed: **Jan. 27, 2000**

(57) **CLAIM**

(51) LOC (7) Cl. **09-03**

The ornamental design for a compressed fabric article package having a simulated van shape, as shown.

(52) U.S. Cl. **D9/308**

DESCRIPTION

(58) Field of Search D9/307, 308; D21/552, D21/558, 560, 424, 434; 206/457; 229/116.1, 116.4

FIG. 1 is a front perspective view of a compressed fabric article package having a simulated van shape of the present invention, showing my new design;

(56) **References Cited**

FIG. 2 is a bottom plan view thereof;
FIG. 3 is a back elevation view thereof; and,
FIG. 4 is a front end elevation view thereof.
